UNITED STATES PATENT OFFICE

2,136,168

FILING DEVICE

Emil Kern, Long Island City, N. Y., assignor to
 Acco Products, Inc., Long Island City, N. Y., a
 corporation of New York

Application August 12, 1937, Serial No. 158,682

7 Claims. (Cl. 40—102)

The invention relates to filing devices and more particularly to readily operable means for detachably clamping blue prints, maps, or the like for vertical filing or display.

5 Drawings, such as are used by architects, builders and engineers, are not easily filed and maintained in accessible arrangement because commonly such drawings are laid flat one upon another in drawers. The improved clamping means 10 is particularly adapted for use in vertical filing cabinets of a type such as are shown in Patents No. 1,867,158 and No. 1,867,159, both issued July 12, 1932, in which the drawings, wall paper or fabric, are suspended in a readily accessible manner and from which they can quickly and conveniently be removed.

20 It is an object of the invention to provide supporting members for a vertical filing device with novel rotatably mounted spring actuated clamp- 25 ing elements.

Another object is to provide novel means to securely clamp drawings or the like to supporting members.

The foregoing and such other objects of the 25 invention as will more fully appear hereinafter as the description proceeds, will be more readily understood from a perusal of the following specification, reference being had to the accompanying drawing, in which:—

30 Fig. 1 is a perspective view of a portion of a filing or display device embodying features of the invention.

Fig. 2 is a fragmentary elevational view of a 35 slidable supporting member showing the improved clamp in disengaged position.

Fig. 3 is a vertical sectional view through the slidable member and clamp.

40 Fig. 4 is a fragmentary elevational view of a slidable member having a modified form of clamp thereon.

The improved clamp, indicated generally at 11, is secured, in a manner to be fully described in detail hereinafter, upon a slidable member 12. The member 12 preferably consists of an elongated strip of sheet material having its upper margin folded rearwardly and downwardly to provide a flange 13. The flange 13 is adapted to overlie the upper edge of a strip 14 forming a part of a hanger arm 15 whereby the member 12 may be freely slid onto or off of the strip 14.

45 The hanger arm 15 may be formed independently of the strip 14 or the arm and strip may be made of a single piece of material stamped or otherwise bent to the required form. An eyelet or journal 50 55 16 is provided at one end of the hanger arm so

that said arm may be mounted for swinging in a horizontal plane.

In use, a plurality of said hanger arms preferably are pivotally mounted in a readily accessible position upon a suitable support within a filing cabinet. To this end a mounting 17 is provided, which, in its preferred form, comprises a channel member having openings 18 in its flanges. The journal 16 of the arm is positioned between the mounting flanges, in alignment with a pair of the openings 18, and a pin 19 is inserted for securing said arm to the mounting. In this manner an independent filing unit supported upon the arm 15 is provided which is swingable there- 10 with.

15 The clamp 11, best shown in Figs. 2 and 3, preferably includes a suitable bracket 21 and a clamping element 22 each of which is provided adjacent one end with spaced apart ears 23—24, respectively, to receive a bearing pin 25. The bracket 21 is rotatably secured by a rivet 26 to the slidable member 12, an embossed bearing surface for the bracket 21 preferably being formed therein. The clamping element 22 has its free end 28 bent outwardly slightly and an elongated opening 29 is provided therein adjacent said end to receive a hanger pin 31 therethrough when in clamping position. The clamping element is held in clamping position by a coil spring 32 carried on the bearing pin 25.

20 The pin 31 preferably is threaded at one end 33 to receive a nut 34 whereby it is rigidly secured to the slidable member 12. Two or more pins 31 and a like number of clamping members 11 are mounted on each slidable member 12. As 25 shown, the drawings or other sheets of material 35 to be secured to the slidable member are suitably perforated adjacent one edge to receive the pins 31. The clamping members 11 are moved from a substantially horizontal ineffective 30 position clear of the sheets 35 (as best shown in Fig. 2) into a vertical position to co-operatively engage over the respective pin 31 to clamp the sheets tightly against the slidable member 12. To remove any or all of the drawings or other 35 sheets of material, the free end 28 of the clamp 40 element is engaged and the clamp element is withdrawn from over the pin 31 and swung into its substantially horizontal position clear of the sheets of material.

45 In the clamp illustrated in Fig. 4, the aperture 29a is cut through one edge of the clamping element 22 thereby permitting said element to be rotated into or out of engagement with the pin 31 without the necessity of raising said clamping 50 55

element to clear the end of the pin 31. The clamp is identical in all other respects with the one previously described.

It is to be understood that various changes may be made in the details of construction and arrangement of parts without departing from the spirit of the invention or sacrificing any of the advantages thereof.

I claim:

- 10 1. In a filing and display device, a slidable member having spaced pins to receive and support sheets and like material, and hingedly mounted clamps rotatably mounted on said member co-operating with said pins to retain said sheets thereon.
- 15 2. In a filing and display device, a unit comprising a supporting arm having means at one end to provide a pivotal support therefor, a member provided with a downturned flange at its upper edge adapted to engage the arm, a plurality of pins on said member to receive and support sheets or other material on said member, and yieldable clamps mounted on said member co-operating one with each pin to retain the sheets in place.
- 20 25 3. In a filing and display device, a unit comprising a supporting arm having means at one end to provide a pivotal support therefor, a member slidable on said arm, a plurality of pins on said member to receive and support sheets or other material, clamps pivotally mounted on said member each having an opening to receive the free end of one pin to secure the sheets to said member.

4. In a filing and display device, a unit comprising a supporting arm having means at one end to provide a pivotal support therefor, a member slidable on said arm, a plurality of pins on said member to receive and support sheets or other material, a plurality of brackets rotatably mounted on said member, and a clamp element mounted in each bracket to co-operate one with each pin to retain the sheets in place.

5. A clamp comprising, in combination, a bracket pivotally secured to a member, a pin on said member, and a clamp element yieldably secured to said bracket movable into engagement with said pin.

6. A clamp comprising, in combination, a bracket pivotally secured to a member, a pin on said member adjacent said bracket, and a movable clamp element mounted on said bracket apertured to receive said pin.

7. A clamp comprising, in combination, a bracket pivotally secured at one end to a member, spaced ears adjacent the other end of said bracket, a bearing pin extending between said ears, a clamp element having an opening at one end, spaced ears on the other end of said element journaled on said bearing pin, means between said bracket and clamp element to urge the free end of the clamp element toward the member, and a pin on said member to extend through the opening in said clamp element.

EMIL KERN.
